T. J. BURTON,
SEWER INLET,
APPLICATION FILED JUNE 26, 1922.

1,434,677.

Patented Nov. 7, 1922.

UNITED STATES PATENT OFFICE.

THOMAS JAMES BURTON, OF MURPHYSBORO, ILLINOIS.

SEWER INLET.

Application filed June 26, 1922. Serial No. 571,067.

To all whom it may concern:

Be it known that I, THOMAS J. BURTON, a citizen of the United States, residing at Murphysboro, in the county of Jackson and 5 State of Illinois, have invented certain new and useful Improvements in Sewer Inlets; and I do declare the following to be a full, clear, and exact description of the invention, such as will enable others skilled in the art 10 to which it appertains to make and use the same.

This invention relates to an improved inlet and cover construction for sewers and analogous devices. It has particular reference 15 to sewer inlets which are located in the gutters and along the curbstones of streets, and the particular improvements in the invention reside in a means for locking the cover plate for the sidewalk manhole or 20 opening of the sewer to the base-ring thereof and also in an improved base-ring and grated inlet construction for the sewer.

The improved locking means for the sewer cover plate is mounted in the sewer inlet 25 part of the base-ring in such a position that it is out of the way and yet is so easily accessible that it may be easily and quickly unlocked when it is desired to remove the cover plate from the sewer opening. At the 30 same time, the locking means is such that when the cover plate having been removed is placed upon the sewer opening, it will be automatically locked. The parts of this mechanism are of very simple construction 35 so that they can be made and fitted together very quickly and easily and so that in making the parts very little if any machine work will be necessary.

In addition to being provided with an 40 improved locking means between the cover plate and base-ring of the sewer inlet, the latter is provided with an improved grate construction for preventing refuse from passing into the sewer inlet and gaining access 45 to the sewer proper.

The device is of simple, strong, durable and inexpensive construction which are qualities that are highly desirable in a device of this character.

50 The novelty of the invention resides in the various details of construction and combination and arrangement of parts which are hereinafter fully described and claimed and shown in the accompanying drawing.

55 In the accompanying drawing which forms a part of this specification:

Fig. 1 is a top plan view of a sewer inlet and cover constructed so as to embody the principles of the present invention.

Fig. 2 is a central vertical longitudinal sectional view of the sewer inlet and cover, said view being taken substantially on the plane indicated by the line 2—2 of Fig. 1.

Fig. 3 is a front view of the sewer inlet and cover, 65

Fig. 4 is a detail sectional view taken substantially on the plane indicated by the line 4—4 of Fig. 2,

Fig. 5 is a detail sectional view taken substantially on the plane indicated by the line 70 5—5 of Fig. 1; and

Fig. 6 is a perspective view of the sewer inlet and cover.

The improvements which form the subject matter of the present invention are intended 75 primarily to be incorporated in an inlet and cover construction for sewers but they of course can be incorporated in analogous devices. However, in the accompanying drawing, they are shown as applied to an inlet 80 and cover construction for sewers, and in the drawing the numeral 1 is used to designate the base-ring of the sewer. This ring is intended to be embedded in the material out of which a sidewalk is constructed over the 85 sewer opening, which is located at a point adjacent the curbstone. The base-ring 1 is provided with a depending annular flange 2 and one side thereof is widened to provide a laterally projecting plate 3. The upper 90

surface of the base-ring 1 and plate 3 is intended to lie flush with the surface of the sidewalk, and the plate 3 is intended to project from the base-ring 1 toward the curbstone and have its free edge disposed flush 95 with the vertical edge of the curbstone. The ring 1 is provided with a countersunk annular shoulder 4 upon which the cover plate hereinafter described is intended to rest. The annular flange 2 at a point intermediate 100 of the ends of the plate 3 is provided with an opening 5, and depending from the plate 3 at the ends thereof are apertured ears or lugs 6. The purpose of these parts is hereinafter described.

105 Disposed beneath the plate 3 and lying flush with or slightly below the surface of the gutter is a plate 7. The ends of this plate 7 are provided with upright flanges or sides plates 8. The upper ends of these 110 flanges or side plates 8 are disposed alongside of the ears or lugs 6 and are apertured

to correspond with the ears or lugs 6 so as to receive bolts 8 or other suitable securing elements by which the flanges or side plates 8 are secured to the ears or lugs 6.

5 The lower side of the plate 3 and upper side of the plate 7 are provided with sockets 9, into which are fitted the ends of grate bars 10. The sockets 9 are disposed along the front edges of the plates 3 and 7, and 10 hence the grate bars 10 are located along the curbstone so as to prevent refuse from passing into the sewer inlet.

Associated with the base-ring is a cover plate 11. This is intended to rest at its 15 outer edge upon the countersunk annular shoulder 4, and it is provided with a depending annular flange 12, the external or outer surface of which is provided with a continuous groove 13. When the cover plate 20 11 is in place upon the base-ring 1, the groove 13 is disposed in the same horizontal plane with the opening 5 in the flange 2 of the base-ring 1. In order to permit easy 25 removal of the cover plate 11 from the base-ring 1, the cover plate 11 is provided with a handle 14, which when not in use is in a lowered out-of-the-way place but which when 30 in use may be pulled upwardly.

Secured in any suitable manner to the 35 lower side of the plate 3 is a housing 15, in which is enclosed and slidably mounted a latch 16. The latch 16 has its inner end projecting through the opening 5 in the flange 2 of the base-ring 1 and is provided 40 intermediate of its ends with an upstanding lug 17 which engages the flange 2 and between which and the end of the housing 16 a coil spring 18 is interposed to maintain the latch yieldably projected. The outer 45 end of the latch 16 projects through an opening in the end of the housing 15 and this end of the latch is provided with a ring 19 or an equivalent element by which the latch may be pulled outwardly so as to 50 retract it. The inner end of the latch 16 is beveled from its upper side and the lower edge of the flange 12 of the cover plate 11 is beveled so that when the cover plate 11 is placed upon the base-ring 1, the latch 16 will be automatically retracted but as soon 55 as the groove 13 is opposite the end of the latch 16, the latter will under the tension of the spring 18 automatically move inwardly into the groove and lock the cover plate to the ring.

The base-ring 1 with the plate 3 and the plate 7 with the flanges or side plates 8, and also the cover plate 11 with the flange 12 having a groove 13 therein, may be molded or cast. The parts of the locking means 60 may be very easily and cheaply made since they are of very simple construction, and hence it will be seen that practically the

whole device can be made without requiring but a very little machine work. The device 65 is therefore of simple, strong, durable and inexpensive construction, which are highly desirable qualities for a device of this character.

From the foregoing description, taken in 70 connection with the accompanying drawing, the construction and use of the invention will be readily understood without further description. It is obvious that various 75 changes in form, proportion, and in the various details of construction may be resorted to without departing from the principle or sacrificing any of the advantages of the invention, and hence it is to be understood that such changes may be made within 80 the meaning and scope of the appended claims.

I claim:

1. In a cover construction for sewers and 85 analogous devices, the combination of a base-ring, a cover plate fitting said ring and provided with a depending annular flange having a continuous groove on the exterior side thereof, and a spring-projected latch mounted upon said ring and projectable into said 90 groove to lock said cover plate upon said ring.

2. In a cover construction for sewers and 95 analogous devices, the combination of a base-ring provided with a depending flange having an opening extending through one side thereof, a cover plate fitting said ring and provided with a depending flange having a continuous groove on the exterior side thereof, said groove being disposed in the same 100 plane with said opening through said flange of said base-ring, a latch slidably mounted upon the lower side of said base-ring, said latch having its inner end extending through said opening and being extendible into said 105 groove to lock said cover plate to said base-ring, and a spring associated with said latch and said base-ring for normally holding said latch projected.

3. In a cover construction for sewers and 110 analogous devices, the combination of a base ring, a cover plate fitting said ring and provided with a depending annular flange having a continuous groove on the exterior side 115 thereof, the ends of said plate being provided with depending lugs, a U-shaped plate disposed beneath the base ring plate and means for fixedly fastening the arms of said U-shaped plate to the base ring plate through said depending lugs, whereby water 120 flowing onto said plate will be discharged into a vertical column directly below said base ring.

In testimony whereof I have hereunto affixed my signature.

THOMAS JAMES BURTON.
